UNITED STATES PATENT OFFICE.

LOUIS B. NUTTING, OF PELHAM, NEW YORK, ASSIGNOR TO POWER SPECIALTY COMPANY, OF NEW YORK, N. Y., A CORPORATION OF NEW YORK.

ANCHORING MEANS FOR SUPERHEATERS.

1,313,326.

Specification of Letters Patent.

Patented Aug. 19, 1919.

Application filed December 11, 1915. Serial No. 66,268.

To all whom it may concern:

Be it known that I, LOUIS B. NUTTING, a citizen of the United States, residing at Pelham, county of Westchester, and State of New York, have invented certain new and useful Improvements in Anchoring Means for Superheaters, of which the following is a full, clear, and exact description.

The invention which constitutes the subject matter of this application relates broadly to means for anchoring superheater units. The invention is particularly adapted for use in locomotive superheaters in which the superheater elements extend longitudinally in the fire flues. In such cases, the shocks incident to sudden stops and starts, coupling the cars, etc., are so severe that there is a tendency for the units to be broken or for the units to loosen their connection with the header and thereby cause leakage. Means are accordingly provided to prevent any displacement of the units and to prevent shocks being transmitted to the junction of the superheater units with the header. The superheater units are, however, so secured that they may be easily removed from the flues.

In a superheater of the type illustrated, suitable means are employed for properly spacing and supporting the superheater elements within the fire tubes. These supporting means or feet rest directly upon the lower side of the fire tubes and the movement of the elements with respect to the tubes, due to extraneous vibrations, results in the feet ultimately wearing or cutting into the fire tubes. This objection, which is a serious one, is entirely overcome with my invention, as the means employed to prevent displacement of the units also possesses the additional function of preventing the superheater element supports from cutting the fire tubes.

In the drawings:

45 Figure 1 illustrates a longitudinal section of a portion of a locomotive or other boiler, showing a nest of superheating units projecting rearwardly into a plurality of boiler flues.

50 Fig. 2 illustrates an end elevation of the boiler, showing the superheating elements and the means for anchoring said elements to prevent their longitudinal displacement and damage by shocks.

55 Fig. 3 is an enlarged detail view of the

hook bolt which secures the superheating elements in longitudinal position.

In more detail, in the drawings, the reference character 10 designates a conventional form of header to which is connected a number of superheating units 11. These units 11 are detachably connected to the header, preferably by expanding the end of the unit in the header. The units extend downwardly and then rearwardly into enlarged 60 flues 12. The portion of the superheater unit or tube extending rearwardly into the flues is, for example, in the form of a coil having return bends at 13. The front ends of the flues are supported by the usual tube 70 sheet 14.

My novel means for anchoring the units against longitudinal displacement to prevent strains occurring at the juncture of the unit and the header and to avoid the 75 superheater unit supports from cutting the flues, I will now proceed to describe.

The stay bars 15 preferably extend across the boiler adjacent to the tube sheet and are secured to the shell 16 by bolts or rivets. 80 There is one of these stay bars for each row of fire tubes, and the bars are located slightly rearward and above the return bends 13 of the superheating elements. Adjacent to each fire tube a hook bolt 18 85 engages the stay bar. This hook bolt extends forwardly over and projects beyond the edge of the stay bar, as shown in Fig. 3. Welded to each of the superheating units at a point adjacent to 90 each return bend is a lug 19. In the construction illustrated, this lug extends upwardly and is bent to engage the hook bolt, as shown in Fig. 3. The end of the hook bolt 18 is threaded to receive nuts 21. After the 95 lugs are in position over the hook bolts, these nuts are tightened to draw the hook bolt into engagement with the stay bar and also to draw the lug 19 into contact with said bar. The second nut constitutes a lock 100 nut.

The above mentioned structure holds the superheating elements in fixed longitudinal position and prevents the stresses which are set up in the superheating units from resulting in strains and possible damage at the juncture with the header. At the same time, the superheater elements are readily removable from the fire flues.

To support the superheater elements in 110

the flues and to properly space the elements, I provide the usual supporting blocks 23 and distance pieces 24. These are preferably sharpened at the ends to offer as little 5 resistance as possible to the flow of gases and in the withdrawal of the elements from the flue.

The above description and the accompanying drawing relates to one embodiment only 10 of my invention. It is to be understood, however, that I do not limit myself to the exact construction shown and described as many changes may be made in point of detail and other embodiments and arrangements resorted to without necessarily deviating 15 from the true spirit and scope of my invention.

What I claim is:

1. A superheater having superheater units 20 adapted to project rearwardly into the boiler flues, in combination with means for relieving said units from the strains incident to vibrations and shocks, said means comprising independently secured stay members and 25 connections between said members and the superheating elements.

2. A superheater comprising, in combination, a header; superheater units having inlet and outlet portions connected thereto 30 and a portion projecting rearwardly into flues; means for preventing strains at the connection of the units and header, said means comprising independent stay members extending transversely of the units, and 35 removable connecting elements between the superheating units and the stay members.

3. In a superheater, a header, and superheater units connected thereto and projecting rearwardly into fire tubes, in combination 40 with means for preventing strains at the connection of the superheating units and said header, the said strains being incident to vibrations and shocks, the said means comprising a plurality of stay members, a plurality of lugs welded to the aforesaid 45 units and extending adjacent to said stay members, and means for connecting said stay members to said lugs.

4. A superheater comprising, in combination, a header, superheating units expanded 50 therein and projecting downwardly and rearwardly into fire tubes, means for removing from the juncture of the header and the units the stresses incident to vibration 55 and shocks, said means comprising a plu-

rality of stay members, a plurality of lugs welded to the aforesaid units and extending adjacent to said stay members, and connecting means between said lugs and stay members.

60

5. A superheater comprising superheater units projecting rearwardly into the boiler flues, in combination with means in the flues for supporting said units, and means for preventing vibrations of said units to prevent the superheater unit supports from cutting into the flues.

65

6. A superheater comprising headers, and superheater units connected to said headers and projecting rearwardly into the boiler flues, in combination with means in said flues for supporting said units, and means for preventing the superheater unit supports from cutting said flues, and for preventing strains upon said units, comprising independently secured stay members connected to said superheating elements.

70

7. In combination with a boiler, of a superheater, comprising a header located in the smoke-box, and superheater units having perforated lugs and projecting rearwardly into a plurality of fire tubes, the ends of said units being expanded into said header, in combination with means for rigidly anchoring said units, comprising cross 85 bars secured to the interior of the smoke-box and provided with projecting bolts thereon, and means for securing the said bolts to the said lugs.

80

8. In combination with a boiler, a superheater comprising a transverse or extension header located in and supported by the walls of the smoke box, and superheater units having perforated lugs and projecting rearwardly into a plurality of fire tubes, 95 the ends of said units being expanded into said header, in combination with means for rigidly anchoring said units comprising a plurality of cross-bars secured to the interior of said smoke box and each provided 100 with a plurality of bolts arranged substantially parallel to the longitudinal axis of said boiler, and means for securing said bolts to said lugs.

90

In testimony whereof I hereunto affix my 105 signature.

LOUIS B. NUTTING.
